CLAIM

The ornamental design for a disk drive tray bezel, as shown and described.

DESCRIPTION

FIG. 1 is a top front and left side perspective view of the disk drive tray bezel showing our new design with the tray depicted in broken lines for illustrative purposes only and forms no part of the claimed design; and,

FIG. 2 is a bottom front and left side perspective view thereof the undisclosed right side view is a mirror image.

The areas of the bezel which have not been completely disclosed in FIG. 1 and FIG. 2 are understood not to be part of the claimed design.

1 Claim, 2 Drawing Sheets*Fig. 1*
